UNITED STATES PATENT OFFICE.

ALEXANDER FERDINAND VICTOR, OF DAVENPORT, IOWA, ASSIGNOR TO VICTOR ANIMATOGRAPH COMPANY, OF DAVENPORT, IOWA, A CORPORATION OF IOWA.

STEREOPTICON.

1,227,507.

Specification of Letters Patent.

Patented May 22, 1917.

Application filed February 26, 1914. Serial No. 821,121.

To all whom it may concern:

Be it known that I, ALEXANDER FERDINAND VICTOR, a subject of the King of Sweden, having declared my intention of 5 becoming a citizen of the United States, residing at Davenport, in the county of Scott and State of Iowa, have invented new and useful Improvements in Stereopticons, of which the following is a full, clear, and 10 exact description.

My invention relates to improvements in stereopticons, and particularly to stereopticons of the type set forth in Letters Patent of the United States, granted to me May 27, 15 1913, Number 1,062,622.

The object of my invention is, principally, to so construct the same that it can be reduced in size and made very compact without detracting from its value and efficiency 20 as a high grade apparatus. Secondarily, it is the object of my invention to support the entire apparatus on a single standard; to so unite the slide-holder, condensing-lenses and projecting lens that they can be separated 25 as a unit from the rest of the apparatus without disturbing their relation, and it is also one of the objects of the invention to attach the means for supporting the condensing lenses to the slide-holder and have 30 it project back into the housing so that it will not come in contact therewith so as to permit better ventilation; and it is another object to provide a tubular support for the projecting lens, and to yieldingly attach 35 said tubular support to the slide-holder so that it may be utilized to clamp the slide in any position to which it may be adjusted. These and other objects and advantages I accomplish by the means hereinafter fully 40 described and as particularly pointed out in the claims.

In the drawings:

Figure 1 is a longitudinal section of my improved stereopticon.

45 Fig. 2 is a transverse section taken on dotted line 2-2, of Fig. 1.

Fig. 3 is a rear end view of the said stereopticon with its base broken away.

Fig. 4 is a side view of the tubular support of the projecting lens, the slide-holder and support for the condensing lenses removed from the apparatus.

Fig. 5 is a detail view showing a fragment of the rear end of the casing of the stereopticon in section.

Fig. 6 is a transverse section taken on dotted line 6-6, Fig. 1, looking in the direction indicated by the drawings.

The base and standard A of my invention is substantially the same as that illustrated 60 and described in my aforesaid Letters Patent. The saddle a is also substantially the same, but a vertically disposed integral circular frame B is supported by said saddle instead of a pillow, as in said patented stereopticon. The forward edge of this circular frame B has an inwardly projecting circumferential flange C, and the inner circumference of this flange has a rabbeted seat c in which the edge of the annulus 9 of the 70 slide-holder elements is seated and secured by suitable screws, as will hereinafter more fully appear.

A cylindrical housing for the arc-lamp used in connection with my improvements is 75 built up back of and is supported by this circular frame B, which comprises an outer cylindrical sheet metal shell 2, the forward end portion of which is secured concentrically to the inner circumference of frame 80 B; the forward edge of this shell 2 being recessed to accommodate the presence of rectangular shaped lugs 3, 3, that are, preferably, about ninety degrees apart and project rearwardly from flange C and are in 85 integral with the same and with said circular frame. The rear end of shell 2 is secured in the outer rabbeted edge of a metal annulus 4. This housing also comprises an inner cylindrical shell 5 which is spaced apart 90 from the outer shell 2 and has its forward edge secured in rabbets in the rear ends of lugs 3, 3, thus leaving an open space between said edge and flange C of the circular-frame B. The rear edges of the inner shell are 95 secured in the inner chamfered edge of the forward side of an annulus k, and said annulus and the circular frame B are connected by long bolts x, x, that hold the parts of the housing in their assembled position. 100

The rear of the housing is closed by a circular head 6 whose circular edges are seated in a suitable depressed seat in the rear side of annulus 4, and secured in place by small screws (not shown) that are tapped into 105 the said annulus. This head 6 is of a truncated cone shape, and in the top of the inclined sides thereof I make a red glass peep-hole 7. In the same horizontal plane as the center of this head 6, diametrically 110

opposite each other I make carbon-holders 8, 8, which latter do not need to be described in detail, because they are substantially the same in construction as the carbon-holders 5 described and illustrated in my aforesaid Letters Patent Number 1,062,622.

The slide holder 9 used by me comprises a circular frame whose outer circumference is about the same in diameter as the inner 10 circumference of frame B, and its rear end is provided with a slight circumferential flange or bead 10 and secured in the rabbeted seat made to accommodate the same to the inner circumference of frame B next the 15 forward side thereof, by means of set-screws 12, 12. This slide-holder is provided with an inwardly projecting flange 13 next its forward side and the forward edge of a circular condenser lens-holder or cradle is 20 secured in the annulus of said slide holder in a suitable manner and the forward condenser lens 14 when seated in said cradle is confined within frame B and bears against said flange 13.

25 The condensing lens holder or cradle consists of two circular frames or rims 15, 16, in which the condensing lenses 14, 18, are seated. The rear rim 16 is angle-shaped in cross-section and is connected to the flat rim 30 of the forward lens 14 by a semi-cylindrical web 19. The rims 15 and 16 and the web 19 are, preferably, made from one piece of sheet metal. Web 19 connects the lower portions of said lenses, and it has a flat segmental spring 21 secured transversely to the inner surface thereof in such manner that its ends project above the upper edge of web 19, and, in their normal positions, bend inward within the perimeter of the lenses. 35 In addition to this spring, I secure a pair of springs 20 to the inner surface of each side of web 19 that are of such dimensions and are disposed and arranged in parallel position inside of and alongside of spring 21, 40 and bear against the margins of the condensing lenses and confine them in proper position in their respective rims. The cradle holding the condensing lenses is separated from the inner shell of the lamp-housing 45 and there is always a circulation of air through the series of openings 22 in the outer shell, and 23 in the inner shell and between the fore-shortened forward edges of the inner shell and the slide holders so as 50 to reduce to a minimum the high temperature created by the burning of the carbons of 55 the arc-lamp in the rear of the housing.

60 The annulus of the slide-holder has corresponding upper and lower guide-lugs 24, 24, projecting forward therefrom. These lugs are placed diametrically opposite each other and their opposing inner surfaces are horizontal. The ordinary slide is inserted 65 transversely in the machine between these lugs 24 and is clamped against the forward

side of the said annulus 9, by the pressure of the rear annular frame 25 forming the rear end of the tubular support of the projecting lens. This tubular support has a frustum shaped metal shell 26, which is 70 greatest in diameter at its rear end, and its rear end is secured to the outer circumference of the annular frame 25, and its forward edges are suitably secured to the outer circumference of an inside ring 27. This 75 ring 27 has a suitable flanged bushing 28 secured to and within the same, and the inner circumference of this bushing is screw-threaded and adapted to be engaged by the outer screw-threaded rear end of a nipple 80 29. The annular frame 25 and the ring 27 are connected by longitudinal bolts 30, which, when tightened up, securely hold said annular frame, ring and shell 26 in their assembled positions. 85

The projecting-lens holder 31 is of a conventional design, and I make no claim to inventorship of the same. Suffice it to say that the rear end of this lens holder has a screw-threaded portion which is removably 90 tapped into the forward end of the nipple 29.

95 The projecting lens holder is secured to the slide-holder by means of screws 32 which are tapped through suitable smoothly bored openings in the annular frame 25, longitudinally into openings in lugs 24, 24. The headed ends of these screws 32 are provided with suitable washers, and between these washers and the forward sides of said annular frame 25, coil expansion springs 33 surround the screws. These springs are of sufficient strength to press the annular frame against the forward ends of lugs 24 and to maintain the projecting lens and projecting- 100 lens-holder concentric to the focal axis of the condensing-lenses, and the arc-light in the rear of the housing. If the thickness of the slide-holder is greater than the length of the lugs 24, the pressure of the rear end 105 of the projecting lens support will be sufficient to hold it in any position to which it may be adjusted. If the slide holder is of such width as to move too freely between the lugs 24, a set-screw, which is tapped down 110 through the upper lug 24, can be manipulated to retain the slide-holder in the position desired. 115

120 The screws 12 that are used to secure the slide-holder in place are tapped through the flange C of the circular frame B and into the lugs 3, 3, thereof, situated above and below the axis of said frame, and the heads of these screws lap over the outer circumference of said circular frame and hold it in 125 place while permitting it to be rotatable. At suitable points 12^a, located diametrically opposite each other, the circumferential edge of the circular frame of the slide-holder is flattened, and by rotating the slide-holder on 130

its axis until these flattened portions are next said screws 12, the slide-holder and parts supported thereby can be removed from the housing by withdrawing the same 5 longitudinally forward a suitable distance. This slide-holder, etc., can be inserted in place by the reversal of these movements.

What I claim as new is:

1. In a device of the class described, a housing 10 consisting of concentric inner and outer perforated shells, a tapering head closing the rear end of the housing, a lamp supported by the tapering head, a frame having lugs secured to the forward end of the 15 housing for securing the frame and housing together, a slide-holder secured in said frame, a cradle in the housing in the rear of the slide-holder, and condensing lenses in said cradle.
2. In a device of the class described, a housing 20 consisting of concentric inner and outer perforated shells, a tapering head closing the rear end of the housing, a lamp supported by the tapering head, a frame having 25 lugs secured to the forward end of the housing for securing the frame and housing together, a slide-holder secured in said frame, a cradle in the housing in the rear of the slide-holder, a pair of condensing lenses in 30 said cradle, and a plurality of springs supported by the cradle and disposed relatively to the lenses.
3. In a device of the class described, a housing 35 consisting of concentric inner and outer perforated shells, a tapering head closing the rear end of the housing, a lamp supported by the tapering head, a frame having lugs secured to the forward end of the housing for securing the frame and housing

together, a slide holder secured in said frame, a cradle in the housing in the rear of the slide-holder, a pair of condensing lenses in said cradle, and a plurality of springs supported by the cradle and disposed relatively to the lenses; one of said 45 springs being flat and others being curved.

4. In a device of the class described, a housing consisting of concentric inner and outer perforated shells, a tapering head closing the rear end of the housing, a lamp 50 supported by the tapering head, a frame having lugs secured to the forward end of the housing for securing the frame and housing together, a slide-holder secured in said frame, condensing lenses and a cradle for 55 holding said lenses consisting of frames in which the lenses are seated, and a web connecting said frames.

5. In a device of the class described, a housing consisting of concentric inner and outer perforated shells, a tapering head closing the rear end of the housing, a lamp supported by the tapering head, a frame having lugs secured to the forward end of the housing for securing the frame and housing together, a slide-holder secured in said frame, condensing lenses and a cradle for holding 65 said lenses consisting of frames in which the lenses are seated, a web connecting said frames, a separating spring attached to the 70 web, and curved lens supporting-springs also attached to the web.

In witness whereof I have hereunto set my hand this 12th day of February, 1914.

ALEXANDER FERDINAND VICTOR.
